UNITED STATES PATENT OFFICE.

HERMAN L. KUTTER, OF HAMILTON, OHIO, ASSIGNOR TO THE BLACK-CLAWSON COMPANY, OF HAMILTON, OHIO.

PAPER-DRIER.

1,130,179.

Specification of Letters Patent.

Patented Mar. 2, 1915.

Application filed August 18, 1914. Serial No. 356,571.

To all whom it may concern:

Be it known that I, HERMAN L. KUTTER, a citizen of the United States, residing at Hamilton, Butler county, Ohio, have invented certain new and useful Improvements in Paper-Driers, of which the following is a specification.

In the ordinary drying of the wet newly formed web in paper mills the usual course is to pass the web partially around a steam-heated drying-cylinder and then partially around a second cylinder located in the same plane of the first cylinder, and so on partially around any desired number of cylinders arranged in a common horizontal plane. The paper, in passing from one drying-cylinder to another passes over suitable guide-rolls. The paper passes around under the first drying-cylinder and then up and over guide-rolls and then down and around the next drying-cylinder, etc. These drying-cylinders, being arranged in a common horizontal plane, take up a great deal of room.

The vapor-driven out from the paper by the heat from the drying-cylinders must escape in some manner so as to eventually get out into the drying-room and escape upwardly therefrom. Very little analysis of this general arrangement of driers will show that the running paper forms roofs over the spaces between contiguous driers, and that the main bulk of the vapor is driven off below these roofs and it can only get out into the drying-room through the tunnels, so to call them, formed by the spaces between contiguous driers and below the paper roofs above these spaces. Quite regardless of the very great width of web in which paper is now being made, it will at once be apprehended that the main part of the vapor thrown from the paper by the driers must move axially from the driers and pass up around the edge of the paper. In the drying of paper by any of the present known methods wet edges have been a constant source of trouble, and the sidewise discharge of the great quantities of vapor has resulted in extraordinary condensation in the drying-room. The importance of this general matter will be apprehended when it is understood that in passing one hundred tons of wet paper over the driers sixty tons of water must be drawn out of the paper in the form of vapor.

Reference has been made to the fact that driers arranged in a horizontal series take

up a great deal of space, giving extended area for the drying-room. It is quite common in modern paper mill construction to lessen the horizontal extent of area required for the driers by arranging several horizontal sets of driers, one above the other. This arrangement saves room but does not lessen in any degree whatever, the trouble above referred to, such as wet edges and the horizontal discharge of vapor into the drying-room before it can possibly find an upward outlet, furthermore, this multiple deck system of driers, has the disadvantage of disposing the driest portions of the running web of the paper under the wetter running portions of the web so that there is always present the tendency for the driest portions of the web to absorb moisture expelled from the wetter portions.

In my improved system of driers I aim to avoid in a great degree, the presence of the horizontal tunnels through which the vapor must move axially of the driers, and to substitute therefor an arrangement of driers permitting the vapor to move mainly in vertical paths to an outlet at the top of the drying-room thus avoiding almost entirely the trouble due to wet edges and to horizontal discharge of vapor into the drying-room. My improved system also very greatly lessens the amount of horizontal area of the drying-room required as compared with any of the usual multiple decks.

My invention will be readily understood from the following description taken in connection with the accompanying drawings in which:

Figure 1 is a side elevation of four columnar sets of driers comprising, all together forty-eight drying-cylinders, the inclosing structure appearing in the plane of line *b* of Figs. 2 and 4: Fig. 2, a plan of the device, the inclosing structure appearing in the plane of line *a* of Figs. 1 and 3: Fig. 3, a side elevation, similar to Fig. 1, but showing the elevators attached: Fig. 4, a plan of the device, similar to Fig. 2, but showing the elevators attached: Fig. 5, a side elevation of the principal parts of one of the elevators: Fig. 6, a horizontal section of the elevator parts in the plane of line *c* of Figs. 3, 5 and 8: Fig. 7, a horizontal section of the elevator parts in the plane of line *d* of Figs. 3, 5 and 8: and Fig. 8, a diagram illustrating the arrangement of the main elevator parts.

In the drawings, ignoring for the present all but Figs. 1 and 2: 1, indicates a skeleton frame-work for the support of the drying cylinders: 2, a vertical series of drying cylinders journaled in boxes supported by the frame-work: 3, a second vertical series of drying-cylinders supported by the frame-work as near as practicable to the first series of drying-cylinders: 4, a third vertical series of drying-cylinders supported by the frame-work somewhat in advance of series 3: 5, a fourth vertical series of drying-cylinders disposed in advance and as near as practicable to series 4: 6, four vertical series of drying-cylinders disposed somewhat in advance of series 5 constituting a duplication of the four series 2, 3, 4 and 5: 7, a web of paper to be dried, this web coming from the left to and up around the lowermost drier of series 3 and then around the lowermost drier of series 2 and so on in serpentine fashion to and up around and over the topmost drier of series 2 and then horizontally to and down series 4 and 5 in serpentine fashion, and then horizontally to and up and down, in serpentine fashion, the driers of group 6, then parting to the right from the base of the driers of group 6: 8, air-jet pipes disposed at the bases of the spaces between the two series 3 and 4 of the driers the two corresponding series of driers in group 6: 9, an air-jet pipe disposed in the base between the drier series 5 and the contiguous driers of group 6: 10, the web of paper leaving the driers: 11, the vertical space between the driers of series 3 and series 4: 12, the vertical space between the drier series 5 and the contiguous drier series of group 6: 13, the vertical space in the center of drier group 6, corresponding with space 11: 14, an inclosing structure surrounding the group of driers and having the top above the driers and adapted for the vertical discharge of vapor through the fully open top of the structure or otherwise: 15, doors to permit access to the inclosing structure: 16, typical gearing, of not unusual character, for transmitting rotary motion to the driers: and 17, top bracing for the side arrangement of the drier-frame.

Now, looking at Fig. 1, it is to be observed that the wet paper, entering the drying-system at 7, serpentines up the two drier series 2 and 3 and then advances horizontally and serpentines down the two series 4 and 5 and then leaves horizontally. Notice that the running web of paper forms a roof extending from the topmost one of driers 2 to the topmost one of driers 5. The vapor rising under this paper-roof may depart sidewise of the general system at any place or places in the space 11 extending from the floor to the paper-roof in question, and the only liability to the wetting of the edge of the web will be incident to the side-

wise departure of such vapor as has not gotten out of space 11 before the paper roof is reached. In the ordinary arrangement of driers there would be thirteen of these paper roofs, none of them so extended as the general roof illustrated but all of them much closer to the field of sidewise departing vapor and therefore having much more tendency to produce wet edges. In the ordinary arrangement of driers the paper roofs in question will necessarily be subjected to most all of the vapor driven off from the driers, while in the present case it is to be noted that the paper roof extending between series 2 and 5 is subjected to the action of only that vapor which cannot depart sidewise from the very extended passage 11, and it is also to be noted that the vapor rising from the outside of the driers of series 2 and 5 is not under any paper roof at all and therefore does not tend to produce wet edges. The inclosing structure 14 confines the vapor driven off by the driers to the immediate neighborhood of the driers and avoids the evils due to the deposit of condensation in the general premises containing the driers. The vertical movement of the vapor in the passage 11, and in the vertical passages outside the driers, is facilitated by the upward jets from pipes 8 and 9, and the withdrawing of the vapor at the top of the system may be at an open outlet or be at any usual or suitable ventilating device.

Thus far reference has been made only to four series of driers 2, 3, 4 and 5. Provision is made for the employment of twenty-four driers, but the system may be extended vertically if desired, without taking up any more room than would be involved in the employment of four driers as ordinarily arranged, and without involving the trouble due to wet edges to much greater extent than would be involved in the employment of only two driers. The addition of twenty-four driers, represented by group 6, simply doubles the effect resulting from the four series 2, 3, 4 and 5 which has been considered.

To aid in assisting the machine-tender in threading the web through the driers, I provide an elevator for carrying him up and down the stacks of driers at the vertical speed of the paper. And by the vertical speed of the paper I do not mean the running speed of the paper but the vertical advance, it being understood that the paper, in moving to and through the driers at a certain speed, zigzags back and forth with a certain vertical advance for the paper. The vertical speed of the elevator, either ascending or descending, is therefore to be in accordance with the vertical advance of the paper and not in accordance with the lineal advance of the paper. This elevator matter I will now explain in connection with Figs. 3 to 8, inclusive, of the drawings, Figs. 3 and

4 repeating Figs. 1 and 2 but adding the elevator mechanism. In connection with this explanation the eye had best be centered on the diagrammatic illustration in Fig. 8, the other figures of the drawings being considered when necessary.

Continuing with the drawings: 18, indicates a fixed vertical column outside and near the drier-frame and constituting an elevator frame-part: 19, a sleeve sliding on this column and constituting an adjunct of the elevator-car: 20, a base carried by this sleeve to support the floor of the elevator-car: 21, the floor of the elevator-car, this floor being illustrated in Figs. 3 and 4 as serving for the four stacks of driers, the four stacks 2, 3, 4 and 5, and also for the duplicating multiple stacks 6: 22, a shaft, illustrated as being disposed across the top of the first group of twenty-four driers, and intended to be turned in correspondence with the vertical advance of the paper and give motion to the elevator: 23, a sprocket-gear on this shaft, near the column 18: 24, an endless chain carried by the sprocket-gear 23 and by an idle sprocket-gear near the base of the column 18, this chain running at a constant speed near column 18, upwardly at the speed of the paper advance at one of its leaves and downwardly at the same speed at the other leaf of the chain: 25, in Fig. 8, a diagrammatic rectangle intended to typify, taken with its accessories, the elevator-car as a whole: 26, a ratchet, with upwardly facing teeth, fixed to the column 18: 27, a spring-pawl carried by the elevator-car and having its toe normally in engagement with ratchet 26: 28, a bolt, carried by the elevator-car and adapted to slide horizontally so that one of its ends may engage with or disengage from the upwardly running leaf of the elevator-chain: 29, a lever carried by the elevator-car and connected with bolt 28 in such manner that the vibration of the lever may move the bolt into and out of engagement with the elevator chain, this lever to be moved by hand by the machine-tender riding on the elevator-car: 30, a horizontal handle-rod by which the machine-tender may rock lever 29, the rod character of this feature of the device permitting of the levers of several elevators being moved by one handle: 31, a lug projecting from pawl 27 and adapted to be engaged by the tail end of bolt 28 to effect the withdrawal of pawl 27 when the bolt is withdrawn by the operation of lever 29: 32, a fixed stop carried by the drier-frame in the neighborhood of the top of the stacks of driers: 33, a tappet-arm connected with lever 29 and adapted, when the elevator-car nearly reaches its desired extremity of upward travel, to engage stop 32 and bring about, in an obvious manner, the withdrawal of bolt 28 from the upward running leaf of the

chain: 34, a horizontal shaft mounted on the car: 35, a sprocket-gear mounted on the shaft and having teeth engaging the downwardly running leaf of the elevator-chain: 36, a ratchet-gear fast with the sprocket-gear 70 35: 37, a spring-pawl carried by the elevator-car and having its toe in engagement with the ratchet-gear 36: 38, a frusto-conical pulley on shaft 22 and serving merely to typify means which may be employed for 75 regulating the speed of the elevator-shaft relative to the rotative speed of the driers: and 39, additional columns carried at the side of the drier-frame for the guidance of the elevator-car. 80

Looking at Figs. 3, 5 and 8, and assuming the elevator-car to be at the floor where it is supported by contact with anything, special provision or otherwise, and assuming that bolt 28 and pawl 27 are both to the left, 85 the left-hand leaf of the chain running downwardly. Under these conditions the elevator-car is at rest; the chain is moving at the speed corresponding with the vertical advance of the paper; the left hand leaf of 90 the chain turns sprocket-gear 35 and ratchet-gear 36 idly; pawl 37 clicks idly. The machine-tender, taking the paper where it enters the driers at 7, proceeds to thread the paper through the vertical series 2 and 3 of 95 the driers. In doing this he actuates, when the proper time comes, lever 29, thus throwing bolt 28 into the right-hand leaf of the chain and permitting pawl 27 to engage ratchet 26. The car now rises at the speed 100 of the vertical advance of the paper, pawls 27 and 37 clicking idly. At any point in the ascent he may shift lever 29 to the left sufficiently to withdraw bolt 28 from the right-hand leaf of the chain, whereupon the 105 elevator-car comes to rest, being supported by pawl 27. He may proceed upwardly, when desired, by shifting lever 29 to the right to again engage bolt 28 with the up-running leaf of the chain. At the top of 110 the trip the bolt will be automatically withdrawn from the up-running leaf of the chain by the engagement of the arm 33 with stop 32 if the tender has not manually shifted lever 29 in order to arrest the upward movement of the elevator-car or to reverse its direction of motion. While the elevator-car is at rest, or while its direction of motion is reversing, the attendant carries the paper over to the topmost drier of series 5 and 115 proceeds to thread the paper downwardly in serpentine fashion on the driers of series 4 and 5. In doing this he will cause the elevator-car to descend which he does by shifting the lever 29 so far to the left that 120 pawl 27 will be entirely free of column-ratchet 26. The load of the elevator-car, and the attendant upon it will now be borne by such tooth of sprocket-gear 35 as engages the down-running leaf of the chain, pawl 37 120

4
5 preventing any reverse turning of this sprocket-gear, so that the engaging tooth of this sprocket-gear becomes, in effect, a bolt carried by the elevator-car and engaging the 5 down-running leaf of the chain so that the elevator-car may descend only at the running speed of the chain, which running speed corresponds with the vertical advance of the paper. The attendant may, whenever 10 it be desired, arrest the motion of the elevator-car as it descends by shifting lever 29 to the right sufficiently to permit pawl 27 to engage column-ratchet 26. Having carried the paper down to the foot of the series of 15 driers 4 he carries the paper forward horizontally at the base of the system and threads it up and down through the stacks 6 of driers, using the elevator in the same manner as has been before described.

20 Briefly, regarding the elevator, the attendant, by manipulating lever 29, may put it in right-hand position to cause the up-running leaf of the chain to carry the car upwardly, or he may put the lever in neutral position 25 to bring the car to rest, or he may put the lever in leftward position to permit the car to be supported by and moved downward with the down-running leaf of the chain. In case of two compound stacks of driers, 30 as indicated in the drawings he may perform these manipulations of lever 29 from the position at any of the stacks of driers, regardless of whether there be two or only one of the elevator-chains so long as the 35 elevator is so arranged as to carry him over the desired routes necessary to thread the paper over the driers.

I claim:—

1. A paper drier comprising a vertical series of closed rotary drying cylinders, a second vertical series of closed rotary drying cylinders disposed alongside the first series, the drying cylinders of the second series having their axes in horizontal planes lying 45 between the horizontal planes of the axes of the first series of drying cylinders, means for producing an upward current of vapor coming from drying paper running in serpentine manner over drying cylinders of the two series alternately, and an open outlet over said two series of driers to permit of the free discharge of the vapor rising therefrom, combined substantially as set forth.

55 2. A paper drier comprising a vertical series of closed rotary drying cylinders, a second vertical series of closed rotary drying cylinders disposed alongside the first series,

the drying cylinders of the second series having their axes in horizontal planes lying between the horizontal planes of the axes of the first series of drying cylinders, means for producing an upward current of vapor coming from drying paper running in serpentine manner over drying cylinders of the 65 two series alternately, and a structure enclosing said two series of drying cylinders and adapted to confine said vapor horizontally and having its upper portion freely open to the atmosphere, combined substantially as set forth. 70

3. A paper drier comprising, a vertical series of rotary drying cylinders adapted for the reception of a web of wet paper in serpentine fashion, a second vertical series of 75 rotary drying cylinders arranged alongside the first series and adapted to receive the partially dried paper from the first series and carry the paper in serpentine fashion in the opposite direction, combined substantially as set forth.

4. A paper drier comprising, a vertical series of rotary drying cylinders adapted for the reception of a web of wet paper in serpentine fashion, an elevator car adapted to 85 travel vertically at one end of said series of drying cylinders, means for moving said elevator car up and down at the speed of vertical advance of the paper, and controlling devices for arresting the motion of the 90 elevator car and for determining its direction of motion, combined substantially as set forth.

5. A paper drier comprising, a vertical series of rotary drying cylinders adapted for 95 the reception of a web of wet paper in serpentine fashion, a second vertical series of drying cylinders disposed alongside the first series and adapted to receive the drying paper from the first series of drying cylinders, an elevator car disposed at the end of said series of drying cylinders and having a platform adapted to support an attendant in position to handle the web of paper on the drying cylinders of either of said series, 105 means for moving said elevator car up and down at the speed of vertical advance of the paper, and controlling devices for arresting the motion of the elevator car and for determining its direction of motion, combined 110 substantially as set forth.
